UNITED STATES PATENT OFFICE.

ALEXANDER LEVIN AND JOSEPH MEDIN, OF CALUMET, MICHIGAN.

DESIGN FOR A WATCHCASE.

53,419.

Specification for Design.

Patented June 10, 1919.

Application filed March 10, 1919. Serial No. 281,880. Term of patent 7 years.

To all whom it may concern:

Be it known that we, ALEXANDER LEVIN and JOSEPH MEDIN, residing at Calumet, in the county of Houghton and State of Michigan, have invented a new, original, and ornamental Design for Watchcases, of which the following is a specification, reference being had to the accompanying drawings, forming part thereof.

Figure 1 is an elevational view of a watch-

case showing our improved design and looking at the back of the watchcase.

Fig. 2 is an elevational view looking at the front of the bezel of the watchcase.

We claim:

The ornamental design for a watchcase, as shown.

ALEXANDER LEVIN.
JOSEPH MEDIN.
